DETACHABLE HANDLE FOR SAUCEPANS OR THE LIKE

Theodore K. Imhoff, Painted Post, N.Y., assignor to Corning Glass Works, Corning, N.Y., a corporation of New York

Filed Mar. 4, 1965, Ser. No. 84,090

Term of patent 14 years

(Cl. D44—29)

Fig. 1

Fig. 2

Fig. 3

Fig. 4

Fig. 5

FIGURE 1 is a top plan view of a detachable handle for saucepans or the like embodying my new design;

I claim:

The ornamental design for a detachable handle for saucepans or the like, as shown.
